CONTAINER

Edward Yellin, Chicago, Ill.

Application July 7, 1944, Serial No. 543,851

1 Claim. (Cl. 220—35)

1

The present invention relates to improvements in containers, and more particularly to a flat circular container of a kind commonly used to contain cosmetics, such as for example powder, rouge, etc.

Containers of the kind to which this invention pertains usually include a shallow circular bottom portion and a circular top or cover portion hingedly connected together at their peripheral edge in such manner as to enable the cover portion to be moved about a pivot into an open or closed position. The bottom and cover portions are each fashioned in a single piece from suitable shape retaining material, such as for example plastics, wood, bone, metal, or the like; and in known types of containers these parts are hingedly connected by means of a separate pin or the like which is extended through complementary hinge elements formed on or otherwise attached to the parts. Obviously the requirement of separate hinge means results in costly assembly operations.

In the present instance, the complementary hinge elements are formed with intermatching means to effect the hinge connection between the parts; hence it is an object of the present invention to provide a container of the character disclosed herein with complementary intermatching hinge elements of a kind capable of being easily and quickly connected together.

Known types of containers of the kind exemplified herein usually require the formation of suitable intermatching means at the free edges of the complementary parts so as to retain the cover portion closed. In order for such intermatching means to be highly effective, it is evident that such means must resist normal forces tending to open the container and as a consequence considerable effort is required to effect intended separation to open the container. Usually opening of such a container is initiated by engaging opposed free edges of the bottom and cover portions with the finger nails and exerting force in opposite directions with the result that the finger nails frequently are broken or otherwise damaged. It is therefore another object of the invention to provide a container with means to retain the cover in a closed position of a kind that will resist normal forces tending to open the container, and at the same time offer but a minimum amount of resistance to forces applied for the purpose of effecting the opening thereof.

Another object of the invention is to provide a container of a kind having a hingedly connected cover movable to open and closed positions, with

2

means to cause said cover to be urged into a fully closed position or a fully opened position upon the initial application of force only.

Another object of the invention is to provide a very practical container of the kind disclosed which is inexpensive to manufacture, easy to assemble, highly efficient in use and easy to manipulate.

Other and further objects of the present invention will be apparent from the following description and claim and are illustrated in the accompanying drawing which, by way of illustration, shows a preferred embodiment and the principle thereof, and which is considered to be the best mode contemplated for applying that principle. Other embodiments of the invention, embodying the same and equivalent principle, may be used and structural changes may be made as desired by those skilled in the art without departing from the present invention and the purview of the appended claim.

In the drawing,

Fig. 1 is a top plan view of a container embodying features of the present invention.

25 Fig. 2 is a diametrical sectional view taken substantially on line 2—2 of Fig. 1.

Fig. 3 is an enlarged fragmentary elevational view of one end of the container as viewed along line 3—3 of Fig. 2.

30 Fig. 4 is an enlarged fragmentary bottom plan view of the container.

Fig. 5 is a fragmentary sectional detail view taken on line 5—5 of Fig. 3, showing the cover closed.

35 Fig. 6 is a sectional detail view substantially like Fig. 5, but showing the cover in open position.

The container illustrated in the accompanying drawing preferably is formed from suitable shape-retaining material, such as for example plastics, and it consists of a bottom portion 11 and a cover portion 12, each of which is substantially circular in shape. The bottom portion 11 is provided with a circular recess or chamber 13, adapted to contain a cosmetic, surrounded by an 40 upstanding flange 14, the outer circular surface 15 of which is spaced inwardly of the periphery of the bottom portion 11. A diametrically arranged rib 16 is formed on the bottom face of 45 the bottom portion 11 and one end of said rib extends upwardly at the peripheral margin of 50 said bottom portion a sufficient distance to dispose its end 17 closely adjacent to but spaced a short distance from the top surface of the bottom portion. A similar rib 18 is formed on the outside

face of the cover portion 12 and this rib likewise extends downwardly over the peripheral margin of said cover portion. When the two parts are assembled in a manner to be described presently, the upstanding circular flange 14 on the bottom portion fits snugly within a circular recess 19 formed on the inside face of the cover portion 12 so as to thereby provide a tightly closed container to prevent spilling of its contents.

As previously noted hereinabove, the cover portion 12 is connected to the bottom portion 11 in such manner as to be moved in an arc towards and away from said bottom portion, preferably as by means of a hinge generally indicated at 21. This hinge has its complemental parts formed integral with one or the other of the two container parts and, as best illustrated in Figs. 3 to 6, it includes a pair of spaced ears 22 extending outwardly radially from the peripheral edge of the bottom portion 11. These ears preferably constitute continuations of the reinforcing rib 16 on said bottom portion. The spaced ears 22 are each formed with a slot 23 on their inwardly disposed faces, and said slots 23 open upon the bottom edges of said ears for a purpose to be more fully explained hereinafter. The reinforcing rib 16 is provided, at the end merging with the ears 22, with a relatively thin wall portion or flap 24 which in the present instance extends between the ears 22 a sufficient distance so as to normally underlie the area in transverse alignment with the slots 23 opening onto the bottom edges of said ears. The continuation 24 of the rib 16 is separated from the ears 22 by slots 25 so as to thereby be entirely free of said ears and thereby be capable of flexing out of its normal plane should force be applied thereto. The ears 22 and flap 24 provide, in effect, a peripheral recess.

One end of the rib 18 on the cover portion 12 is provided with a depending portion 26 of sufficient width to extend freely into the peripheral recess between the ears 22 on the bottom portion 11 when the cover is mounted over the bottom portion. The part 26, which constitutes one element of the hinge structure, is formed on its lateral edges, and adjacent its bottom edge, with outwardly extending bearing portions 27 which extend into and are journaled within the bearing slots 23 in the lugs 22.

Upon reference to Figs. 5 and 6, it will be noted that the cover portion 12 is hingedly mounted, in a manner to be described presently, and by means of the structure described hereinabove, to the bottom portion 11 so as to be capable of being pivotally moved into an open or closed position with respect to said bottom portion. Assembly of the cover portion and the bottom portion preferably is accomplished by initial insertion of one of the bearing journals 27 into a related bearing slot 23. The flap 24 is then flexed downwardly sufficiently to enable the other bearing journal

27 to be inserted into the open end of its related bearing slot 23 whereupon, when the parts are released, the flap 24 returns to its normal position to prevent separation of the parts.

When the cover portion is in its closed position, as best illustrated in Fig. 5, the bottom edge 28 of its depending portion 26 bears tightly against the flap extension 24 on the bottom portion and the cover is thereby urged into and held in such closed position by the resiliency of said flap. When the cover portion is to be moved into open position, the initial resistance of the flap 24 is overcome whereupon said flap again acts upon the depending portion 26 to urge the cover into its fully opened position, as illustrated in Fig. 6. Thus it will be observed that applicant has provided a hinged structure embodying novel structural characteristics affording means to insure a full closing of the container and full opening thereof with the application of but a minimum amount of effort.

The cover is retained in its closed position by frictional coaction between the outside surface 15 of the circular flange 14 and the inside wall of the cover recess 19. Such frictional coaction is attained through slight flexing of the depending hinge element 26 during the closing operation at which time the circular wall of the recess 19 is forcibly urged downwardly over the outside surface 15 of the circular flange 14. To open the container force is applied by any means, such as by the fingers of the user, to the opposed shoulders 17 and 29 at the ends of the reinforcing ribs 16 and 18 respectively, which force is sufficient to cause initial separation of the cover from the circular flange 14, whereupon the resiliency of the hinge element effects further opening into fully opened position.

It should be apparent that applicant has provided a novel container embodying structural features particularly intended to simplify the operations involved in manufacture and to reduce the costs of manufacture and that the invention is capable of being embodied in forms other than the precise construction disclosed herein without departing from the spirit of the invention or the scope of the appended claim.

I claim:

50 A container having a bottom portion and a cover portion, a pair of ears extended outwardly from an edge of the bottom portion, a bearing slot on the inside face of each ear and opening onto their bottom edges, a complemental element on an edge of the cover portion disposed between said ears, means on said element engageable in and rested at the upper ends of said slots, and means 55 in the bottom portion lying in the bottom plane of and extended between said ears beneath the complemental element to prevent unintended withdrawal of said engageable means.

EDWARD YELLIN.
